UNITED STATES PATENT OFFICE.

SAMUEL BUCHSBAUM, OF CHICAGO, ILLINOIS.

DESIGN FOR A FINGER-RING OR SIMILAR ARTICLE OF JEWELRY.

53,062.

Specification for Design.

Patented Mar. 11, 1919.

Application filed April 4, 1918. Serial No. 226,750. Term of patent 3½ years.

To all whom it may concern:

Be it known that I, SAMUEL BUCHSBAUM, a citizen of the United States, residing at Chicago, in the county of Cook and State of Illinois, have invented a new, original, and ornamental Design for a Finger-Ring or Similar Article of Jewelry, of which the following is a specification, reference being had to the accompanying drawing, forming part thereof.

Figure 1 is an elevation of a finger ring or similar article of jewelry, showing my new design, and

Fig. 2 is an end view of a ring having said design.

I claim:

The ornamental design for a finger ring or similar article of jewelry, substantially as shown.

SAMUEL BUCHSBAUM.
